STEAM-TURBINE.

1,082,886.

Specification of Letters Patent.

Patented Dec. 30, 1913.

Application filed February 4, 1913. Serial No. 746,167.

To all whom it may concern:

Be it known that I, FREDRIK LJUNGSTRÖM, a subject of the King of Sweden, residing at 2 Drottningholmsvägen, Stockholm, in the 5 Kingdom of Sweden, have invented certain new and useful Improvements in Steam-Turbines, of which the following is a specification.

The parts of turbines which are heated by the actuating fluid tend to displace by their consequent expansion the labyrinth packings and blade rings carried thereby. Such expansion and displacement are especially injurious in the case of discharging disks inserted between the turbine wheel and the casing, such disks being directly acted on by the steam or other heated fluid and provided with labyrinth packings on their inner faces, which will naturally be moved in line with the axis of the shaft and toward the rotary turbine disks. As a result, a greater normal interval must be provided between these parts on both sides of the turbine than would otherwise be necessary or than is best for its operation; unless some means of compensation be employed. Also such means are needed to keep the said intervals constant and therefore properly efficacious, notwithstanding the changes 30 in temperature of the discharge disks. As such compensating means I employ conoidal connecting rings expansible under the influence of heat and interposed between the turbine casing and the discharging disks, 35 the said ring tending to flatten as they expand and thereby operating to draw back the discharging disks, compensating for the expansion of said disks before mentioned and maintaining unchanged the intervals 40 between these disks and the rotary turbine. Connections of the same kind are made when desirable between the turbine casing and the turbogenerator casing exterior thereto.

In the accompanying drawings, Figure 1 45 represents a vertical central section of a turbine and its casing, embodying my invention; and Fig. 2 represents a similar view of a turbine casing and exterior casing, with connections as above, also embodying 50 my invention.

The turbine-casing *a* supports within it the discharging disks *b* having internal chambers supplied with steam by tubes *d*, this space communicating with the spaces of

the two turbine disks *e*, which rotate in opposite directions with their alined shafts *f* and are separated from disks *b* by labyrinth packings *n*.

Conoidal connecting ring *g* having their larger diameter normally inward toward the turbine connect the two disks *b* to the proximate parts of casing *a*. They have reinforced, and rounded edges which fit pivotally into correspondingly shaped grooves of the said disks and casing. The larger and inner part of each ring being more exposed to the steam than the outer part is more greatly expanded by the heat, tending to give the ring a flat or annular disk form and thereby to draw the connected discharge disk away from the proximate turbine disk. Thus the expanding action of the heat is made to neutralize itself and maintain an interval of constant breadth between the discharge disk and turbine disk. This compensating action is the same for both discharge disks and equal on both sides of the turbine, which therefore works regularly and without accidental variation.

As shown in Fig. 2, the conoidal rings *g* 80 may also be employed to connect the turbine casing *a* with an outer casing *l* which supports the turbogenerators *k*. This will be useful whenever the casing *a* is heated considerably more than any surrounding parts, for example, when exhaust steam of back pressure turbines is used. In this instance the lateral expansion of the casing *a* might cause injury if there were no intervening part that could yield between it and the frame *l*, hence there is a real advantage in the rings *g*, which correspondingly change their form and permit such expansion.

In the construction shown by Fig. 1 the rings *g* will similarly permit the outward 95 expansion of the disks *b* besides drawing them in that direction, as before described. The inclination of the conoidal rings should in either case be such that lines drawn at right angles thereto from the larger peripheries 100 of said rings will cross each other on the axial line of the shafts *f* in the middle of the turbine, see broken lines *i* of Figs. 1 and 2. There will be a less degree of withdrawing action on the discharge disks if a 105 different inclination be chosen.

The rings *g* may be somewhat varied in form and need not always be pivotally con-

nected at their edges. It is only necessary that their securing points in the two parts lie on different radii.

Having thus described my invention, what I claim as new and desire to secure by Letters Patent is:

1. In combination with two parts of a turbine structure arranged in parallel planes transversely to the axis of the shaft, a connecting device between said parts, expandible under the action of heat and adapted to compensate for the movement of one of said parts by heat-expansion, the said device being connected with the said two parts at points lying on different radii.

2. In combination with a casing, a part of a turbine structure within the same subject to the heating action of the actuating fluid with consequent expansion and a connecting 20 conoidal ring.

3. In combination with a turbine casing, a discharging disk arranged to be heated by the actuating fluid, a turbine-disk in proximity thereto, and a conoidal ring connecting said discharging disk to said casing and adapted to expand unequally for drawing back said discharging disk to compensate for

the displacement of the operative surface of the latter by expansion.

4. In combination with the rotary disks of a turbine, a pair of relatively stationary discharging disks in proximity thereto, having steam chambers, means for supplying said chambers, a casing and a pair of conoidal 35 expandible rings connecting said discharge-disks and casing, the larger parts of said rings engaging the said disks and by the greater expansion of such parts operating to flatten and draw back the discharge-disks as set forth.

5. In combination with a grooved discharge-disk and a grooved casing, a conoidal connecting ring reinforced and rounded at its edges which fit pivotally into said grooves, the larger edge being in engagement with said disk, means for supplying steam to the latter and a rotary turbine in proximity thereto.

In testimony whereof I have affixed my signature in presence of two witnesses.

FREDRIK LJUNGSTRÖM.
